EVAPORATOR

Joe E. Talton, Crossett, Ark., assignor to Crossett
Paper Mills, Crossett, Ark., a corporation of
Arkansas

Application March 21, 1940, Serial No. 325,124

1 Claim. (Cl. 159—20)

This invention relates to a new and improved type of evaporator for concentrating liquids and more particularly to a new and improved type of multiple effect evaporator.

One of the objects of the invention is to provide an evaporator or evaporator system for concentrating liquids which is much more efficient than evaporators or evaporator systems now in use.

Still another object of the invention is to provide a new and improved method and apparatus for the evaporation and concentration of liquors employed in the paper industry for digesting or otherwise treating paper pulp.

Still another object of this invention is to provide a new and improved method and apparatus of the character described having an increased capacity.

Other features and advantages of the invention will be apparent by reference to the following description in conjunction with the accompanying drawing in which:

Figure 1 represents diagrammatically a multiple effect evaporator as illustrating the present invention;

Figure 2 is a representation somewhat diagrammatically partly in section and with parts broken away of a single evaporator body or unit.

The evaporator shown in Figure 1 is a five body, long tube, vertical, film type, quadruple effect evaporator. The evaporator is arranged to operate as a quadruple effect with two bodies in the first effect and one body in each of the second, third and fourth effects.

As shown in Figure 2, each evaporator body consists of a bundle of long, small diameter tubes 10 surrounded by a steam chest 12. The bottom of the tube bundle is connected to a cone 14 through which the liquor enters the tubes and the tops of the tubes 16 connect into a large vapor chest or dome 18. Any condensation from steam chest 12 is withdrawn through a conduit or pipe 20. Steam enters steam chest 12 through a conduit or pipe 22. The condensate is withdrawn from the vapor chest or dome 18 through a conduit 24. Vapors are withdrawn from the chest or dome 18 through a conduit 26. It will be understood that any other suitable arrangement of conduits may be employed to accomplish the same result. The invention herein does not reside specifically in the construction of the evaporator body and the general details thereof are given merely for convenience in describing the evaporator system.

Referring again to Figure 1 the four effects of

the evaporator are indicated generally by the numerals I, II, III and IV. Each effect except effect I comprises one evaporator body of the type previously described. Effect I comprises two evaporator bodies illustrated as evaporator body I—A and evaporator body I—B. Starting with effect I the domes of evaporator bodies I—A and I—B are connected to the steam chest of II effect through catch-all 28 and 30, respectively. 10 The conduit 32 connects the dome of evaporator body I—A to catch-all 28. Catch-all 28 in turn is connected as shown by a conduit 34 to conduit 36 which in turn leads to the steam chest of II effect. A conduit 38 connects the dome of 15 evaporator body I—B with catch-all 30 which in turn is connected to the steam chest of II effect through circuit 36.

The dome of II effect is connected to the steam chest of III effect through a conduit 40, a catch-all 42 and a conduit 44. The dome of III effect is connected to the steam chest of IV effect through a conduit 46, a catch-all 48 and a conduit 50. The dome of IV effect is connected to barometric condenser 52 through a conduit 54, 20 a catch-all 56 and a conduit 58. Connected in this manner the steam chest of II effect acts as a condenser for the vapor from the domes of evaporator bodies I—A and I—B. The steam chest of III effect acts as a condenser for the vapor from II effect and the steam chest of IV effect acts as a condenser for the vapor from III effect. The vapor from IV effect is condensed in the barometric condenser 52. The catch-alls 28, 25 30, 42, 48 and 56 serve to remove any water condensing from the vapor.

With this condenser action on each effect the dome pressures preferably range from approximately 14 lbs. per square inch in evaporator bodies I—A and I—B to 3 lbs. per square inch in 30 II effect, to 10 inches of vacuum in III effect to 24.5 inches of vacuum in IV effect. In other words, water is evaporated from the liquor in each effect at the temperature corresponding to the dome pressure in that effect. Live steam is 35 preferably added to the steam chest of evaporator bodies I—A and I—B at from 32 to 40 lbs. per square inch pressure. The difference in temperature of the steam in the chest and the liquor in the tube causes heat to flow from the steam chest through the tube walls to the liquor where it vaporizes or boils off water from the liquor. The water vapor from the domes of evaporator bodies I—A and I—B is carried to the chest of 40 IV effect where it gives up heat to vaporize more water at a lower pressure and temperature. This

continues in progression to the last effect where vapor is drawn off to the barometric condenser.

The flow of the liquor through the evaporator unit is in the opposite direction to that of the steam or vapor. The weak liquor feed is divided to the III and IV effects. The division of the feed liquor to these two effects is controlled by the operator with IV effect usually taking more than III effect. The feed liquor passes up through the tubes 10 of III and IV effects where some water is evaporated from the liquor. The water vapor, being lighter than the liquor, leaves at the top of the dome in each effect while the liquor flows from the bottom of the dome to pumps and is pumped to II effect.

As illustrated in the diagrammatic drawing of Figure 1, the weak black liquor is pumped by a pump 60 through a line 62 which carries it to a line 64 entering the tubes 10 of IV effect and controlled by a valve 66 and also to a line 68 entering the tubes 10 of III effect and controlled by a valve 70.

As previously explained, the weak liquor vaporizes in the tubes of III and IV effects, the vapor passing to the domes 18 of each. The partially concentrated liquid in each dome is withdrawn through suitable conduits. Thus, as shown, a conduit 72 withdraws the residual liquid from the dome of IV effect, conduit 72 being controlled by a valve 74 and merging with a conduit 76 from trap 56. The entire residual liquid is pumped by means of a pump 78 through conduit 80 to the tubes 10 of II effect where further evaporation takes place.

The partially concentrated liquid from the dome of III effect passes through conduit 82 and merges with the liquid from trap 48 delivered through conduit 84. The total feed liquor is then pumped by means of pump 86 through conduit 88 to conduit 80 where it merges with the feed liquor from IV effect and is delivered to the tubes 10 of II effect.

The residual liquid from the dome of II effect passes through conduit 90 and merges with the liquid from conduit 92 delivered from trap 42. The total liquid is then pumped by means of a pump 94 through a conduit 96 to the tubes 10 of evaporator body I-B. The liquid from the dome of evaporator body I-B passes through conduit 98 and merges with the liquid from trap 38 delivered through conduit 100. The total remaining liquid is then pumped by means of a pump 102 through a conduit 104 to the tubes 10 of evaporator body I-A. The liquid from the dome of evaporator body I-A passes through conduit 106 and merges with the liquid passing through conduit 108 delivered from trap 28. This residual liquid has now attained its desired state of concentration.

The concentrated liquid is passed through a liquor discharge float control 110 and a conduit 112 to a flash tank 114 where any residual vapors are removed and passed to the dome of II effect evaporator body through conduit 116. The flash tank 114 serves to remove more vapor and lower the temperature of the liquor from I-A before discharging to the storage tank. From flash tank 114 the concentrated liquid passes through conduit 118 and is pumped by means of pump 120 through conduit 122 to any suitable storage.

During the course of the operations just described condensation is taking place in each of the steam chests of each of the evaporator bodies. As illustrated in Figure 1, the condensate from the steam chest of IV effect is withdrawn

5 through a conduit 124 which merges with another conduit 126 from trap 128. The total condensate is passed through a valve 130 and pumped to a drain, sewer, storage or the like by means of a pump 132.

The condensate from the steam chest of III effect is withdrawn through a conduit 136 and a conduit 138 to trap or flash tank 128. Any vapors occluded or dissolved in this condensate are 10 removed by passing the condensate through trap 128 from which the vapors can escape through conduit 134 to conduit 50.

The condensate from the steam chest of II effect passes through conduit 140 to a trap 142 15 where any vapors can escape through conduit 144 to conduit 44. From trap 142 the condensate passes through conduit 146 to conduit 138.

The condensate from the steam chest of evaporator body I-B passes through a conduit 148 20 and merges with the condensate from evaporator body I-A which is carried from the steam chest of evaporator I-A through conduit 150. The total condensate is then pumped by means of pumps 152 and 154 through a conduit 156 to storage or it may be used for any other suitable purpose. The flow of the condensate from evaporator bodies I-B and I-A is controlled by valves 158 and 160.

In order to facilitate the description the conduits or pipes containing the liquid which is being concentrated by the evaporator are shown in heavy lines. The condensate conduits are shown in dotted lines and the steam or vapor conduits are shown by double lines in the drawing.

35 A particular feature of the present invention is the use of a reflux system shown by the conduit R controlled by the valve V and connecting conduits 68 and 80. The use of this reflux system causes a part of the liquid entering II effect to 40 be diverted and injected into the feed liquor entering III effect. This reflux system only requires a line connecting the feed line entering the bottom of II effect with the feed line entering the bottom of III effect. The higher pressure carried in II effect causes the reflux to flow back to III effect without the aid of a pump. This very simple expedient has provided greatly improved results. For example, in one installation by employing a reflux system of the character just described it was possible to increase the overall coefficient of heat transfer of the evaporator by about 26% and this meant an increase in capacity of about 19%.

55 While the invention is not limited to any theory it is believed that the enormous improvement resulting from the invention may be attributed to the following factors. The performance of an evaporator of this type is dependent upon the flow of heat from the steam in the chest through the tube walls to the liquor (as explained in connection with Figure 2). The flow of heat under these conditions is controlled by three factors, namely, (1) the area of heating surface; (2) the total working temperature drop; and (3) the coefficient of heat transfer. The heating surface is a fixed quantity and in a typical evaporator body may be, for example, 3600 sq. ft. The total working temperature drop is also fixed, being controlled by the condenser capacity and the maximum steam pressure. To alter either of these in order to secure increased capacity is an expensive undertaking.

70 The third factor, namely, the coefficient of heat transfer is in turn governed by three other factors, namely, (1) the steam film resistance be-

tween the steam and the metal wall; (2) the resistance of the metal itself; and (3) the liquor film resistance between the metal wall and the liquid which is being concentrated. Since the liquor film resistance is by far the largest of the three, the first two factors may be considered negligible.

The liquor film resistance is in turn dependent upon two factors, namely, (1) the viscosity of the liquor at the prevailing concentration and temperature; and (2) the turbulence or velocity of the liquid at the wall of the tube. In other words, the greater the turbulence or velocity the greater is the heat transfer. Thus it has been found in accordance with the present invention that the heat transfer in III effect can be almost doubled by taking a part of the liquor that was entering II effect and injecting it into the feed liquor entering III effect.

This reflux liquor is a mixture of the liquor leaving III and IV effects and is at a lower temperature and a higher concentration than the feed liquor to which it is added. The reflux preferably amounts to approximately 23% of the total fed to the unit. The increased volume of liquor passing through III effect due to the reflux would increase the velocity in the tube and thus increase the heat transfer. The higher concentration and lower temperature of the reflux, however, would make the liquor more viscous and tends to offset the heat transfer gained by the increased velocity. Hence, the difference in temperature and concentration of the reflux and the feed liquor probably results in a different and more turbulent type of flow which gives the large increase in heat transfer gained by the use of the reflux.

The advantages of the invention will be further illustrated but it will be understood that the invention is not limited by the following examples, showing comparative test runs with and without the use of the reflux together with heat balances calculated and tabulated to show the conditions in each body of the evaporator unit when operating with and without the reflux.

The evaporator unit upon which the reflux was developed and tested was a Swenson 5-body, long tube, vertical, film type quadruple effect evaporator designed and guaranteed to concentrate 133,000 lbs. of kraft mill black liquor hourly, containing 16% total solids at 160° F., to 38,600 lbs. of concentrated liquor hourly discharged from I-A effect at 55% total solids and 220° F. The evaporation rate under these conditions is 94,400 lbs. per hour. The steam required for the above performance was not to exceed 30,500 lbs. per hour. The evaporative economy for the above conditions is 3.09 lbs. of evaporation per pound of steam.

The evaporator was arranged to operate as a quadruple effect in the manner already described and as illustrated in Figure 1.

Test No. I was made without the reflux and with the evaporator operating close to capacity. Test No. II was made using the reflux and with the evaporator again operating close to capacity. Other tests were made under varying conditions of load but as the results confirmed with heat balances shown in the tests herein described, the other tests are not tabulated. The steam and vapor pressures were calculated from the pressures. The liquor temperatures and concentrations were measured directly.

The results for test No. I were as follows:

TEST NO. I

Reflux not being used

Evaporator effect	I-A	I-B	II	III	IV	Total overall

* Pounds.

* Inches.

Feed liquor to III and IV effects @ 200° F. and 16.1% T. S. @ 8.92 #/gal.

184 G. P. M. feed to IV effect.

126 G. P. M. feed to III effect.

Total heat transfer in all effects = 117,965,000 B. T. U./hr.

Overall coefficient of heat transfer = 117,965,000 = 247 B. T. U./sq. ft./°F./hr.

3600×132

Total evaporation = 118,735 #/hr.

Total steam supplies = 35,800 #/hr.

118,735 ÷ 35,800 = 3.32 pounds evaporation per pound of steam.

The heat balance shows that the refluxing of the feed liquor to III effect increases the coefficient of heat transfer in that effect from 165 to 313 B. t. u./sq. ft./°F./hr. This increase in heat transfer allows III effect to do more work with less temperature differentiation. The evaporator automatically readjusts itself and gives IV effect more temperature differentiation thus allowing it to do more work.

The reflux system just described is not a re-circulating system as it takes a mixture of the

liquid from III and IV effects and adds it to the feed liquor entering III effect. The feed liquor was at a temperature of about 200° F. and approximately 16% total solids. The reflux liquor was at a temperature of about 175° F. and about 25% total solids. The temperature of the reflux liquor was below that of the liquor entering III effect. The concentration of the reflux was above that of the liquor entering III effect.

The reflux apparently increases the heat transfer coefficient in III effect by increasing the velocity through the tubes. The velocity is apparently increased for two reasons, namely, (1) the reflux increases the velocity by increasing the quantity of liquor passing through the tubes. This is accomplished without increasing the evaporation per unit of feed enough to unbalance the evaporators, as there is very little evaporation from the reflux liquor; (2) the reflux probably changes the type of flow through the tubes. In numerous tests it has been found that there are three distinct types of flow in evaporator tubes, as follows: (a) The spurt type flow; (b) The spurt and spray type flow; and (c) The spray type flow.

The spurt type flow is the same type of flow that occurs in a glass of water full of air pockets. It consists of a bubble of liquor then a bubble of air. This type of flow gives the highest coefficient of heat transfer because it has the highest velocity for a given rate of flow.

The spurt and spray type flow is similar to the spurt type of flow except that the air pockets are carrying a spray of the liquid in between the bubbles of liquid. The coefficient for this type of flow is not as high as for the spurt type because the velocity per unit of volume is not so great. The spray type of flow is similar to the flow obtained by pointing a water hose straight up in the air. This type of flow has the lowest velocity per unit volume and therefore the smallest coefficient of heat transfer.

The flow in IV effect is apparently the spray type since a large part of the evaporation occurs as "flash" from the heat of the feed liquor. The flow in III effect is most probably of the spurt and spray type since there is not so much flash evaporation. Addition of the reflux liquor to the feed liquor in the bottom of III effect with the reflux at a lower temperature and a higher concentration of total solids apparently changes

the flow to the spurt type further increasing the velocity over the added velocity due to the added volume of the reflux and thus increasing the coefficient of heat transfer. As previously indicated, while the invention is not limited to any theory, it is believed that this is the explanation of the large increase in the heat transfer coefficient for III effect. If the type of flow in the tubes did not change, the low temperature and higher concentration of the reflux liquor would increase the viscosity of the liquor in the tubes and tend to offset the heat transfer gained by the increased velocity due to the greater volume. Regardless of whether or not this is the correct explanation the use of the reflux has resulted in an increase in capacity in one installation, as already stated, of approximately 19%. It will be recognized that this is a tremendous increase in an evaporator system of this type.

The invention herein described is particularly applicable to the concentration of liquids containing solid materials therein and especially of the weak black liquors which result from the kraft or sulfate process of preparing paper pulp. For reasons of economy it is essential that the weak black liquor be concentrated in order that it may be used again.

It will be understood, however, that the invention is applicable to the concentration of other liquids or of other mixtures of liquids and solids. Likewise many variations may be made in the type of apparatus or equipment employed without departing from the invention.

Having thus described the invention, what I claim as new and desire to secure by Letters Patent of the United States is:

In a multiple effect evaporator for concentrating liquids, a plurality of evaporator tube units comprising five units maintained at successively higher temperatures and pressures, means for feeding a liquid to be concentrated into the fourth and fifth units maintained at lower temperatures and pressures than the other three units, means for successively passing partially concentrated liquor from the fourth and fifth units to the third, second and first units, and means for returning a portion of the partially concentrated liquor from the feed liquor to the third unit to the feed liquor to the fourth unit.
